(57) **CLAIM**

I claim the ornamental design for a handheld skin therapy tool, as shown and described.

DESCRIPTION

FIG. 1 is a perspective view of a handheld skin therapy tool; FIG. 2 is a first side view of the handheld skin therapy tool; FIG. 3 is a second side view of the handheld skin therapy tool;

FIG. 4 is a bottom view of the handheld skin therapy tool; FIG. 5 is a top view of the handheld skin therapy tool;

FIG. 6 is an enlarged first end view of the handheld skin therapy tool; and,

FIG. 7 is an enlarged second end view of the handheld skin therapy tool.

The structure of the handheld skin therapy tool shown in broken lines forms no part of the claimed design.

1 Claim, 4 Drawing Sheets
